Attn:

UNITED STATES PATENT OFFICE.

OSCAR Z. COUTANT, OF SPRINGFIELD, ILLINOIS.

DESIGN FOR A TOOL-BODY.

47,585.

Specification for Design.

Patented July 20, 1915.

Application filed July 7, 1913. Serial No. 777,744. Term of patent 7 years.

To all whom it may concern:

Be it known that I, OSCAR Z. COUTANT, a citizen of the United States, residing at Springfield, in the county of Sangamon and State of Illinois, have invented a new, original, and ornamental Design for Tool-Bodies, of which the following is a specification, reference being had to the accompanying drawing, forming a part thereof.

Figure 1 is a perspective view of one side

of a tool body showing my new design; Fig. 2 is a perspective view of the other side of a tool body showing my new design.

I claim:

The ornamental design for a tool body, as shown.

OSCAR Z. COUTANT.
